UNITED STATES PATENT OFFICE.

CHARLES GARNISS, OF NEWPORT, RHODE ISLAND.

TOY.

Application filed April 18, 1922. Serial No. 554,755.

To all whom it may concern:

Be it known that I, CHARLES GARNISS, a citizen of the United States, residing in Newport, in the county of Newport and State of Rhode Island, have invented certain new and useful Improvements in Toys, of which the following is a specification.

My invention consists in a new and useful improvement in toys, and is designed to provide a figure wheeled toy which can be rolled upon a stretched cord or upon a supporting surface.

The particularly novel features of my device are the eccentricity of the grooved wheels upon which the figure is mounted and which impart a rocking motion to the figure, and the folding handle which serves when folded as a counter-poise when the toy travels upon a cord, and serves when extended as a means for pushing the toy when it travels upon a surface.

I have illustrated in the drawing filed herewith one specific embodiment of my invention, the details of construction of which are hereinafter fully described, but the invention is capable of a variety of forms of embodiment, and it is to be understood that I do not consider the invention limited to the specific embodiment herein described but refer for its scope to the claims appended hereto.

In the drawing:

Fig. 1 is a side elevation of my toy indicating it arranged to travel upon a cord.

Fig. 2 is a similar view indicating it arranged to travel upon a supporting surface.

Fig. 3 is a cross section of the handle.

Fig. 4 is an end elevation of the lower portion of the toy.

Fig. 5 is a side elevation of a portion of the handle.

In the drawing, the toy is shown as a grotesque figure 1 with a slot 2 in its bottom in which are mounted eccentrically two wheels or rollers 3, 3, having circumferential grooves 4, 4. The figure 1 is provided with a jointed handle comprising the two parts 5 and 6. The part 5 is pivotally attached to the figure 1 by a pin 7 and is provided at its outer end with a rectangular orifice 8. The part 6 is provided at one end with a circular orifice 9 and a slot 10 in communication therewith. A flat pin 11 is snugly received through the orifice 8 and extends through the circular orifice 9 or the slot 10 of the part 6, and is held in position by the head 12 and outwardly bent portions 13, 13.

When the toy is to run upon a cord, the handle is folded, as shown in Fig. 1, by so adjusting part 6 that the pin 11 will be received through the circular orifice 9, then turning part 6 so that it overlies part 5, and then adjusting part 6 so that the pin 11 is received through slot 10. When the pin 11 is so placed, the part 6 is held in position above part 5. The handle, when thus folded, forms a balance weight or counter-poise to maintain the toy in position upon the cord.

When the toy is to run upon a supporting surface, it will be obvious that the handle can be extended, as indicated in Fig. 2. When the handle is in this position, it will be seen that the part 6 is maintained in extended position by the co-action of the pin 11 and the slot 10.

It will be noticed that when the parts are in the position shown in Fig. 1, the weight of the part 6 tends to hold it in position, locked against accidental displacement, and when the parts are in the position shown in Fig. 2, the pushing impulse upon the handle tends to hold the part 6 in position, locked against accidental displacement.

It will be apparent that the eccentricity of the mounting of the wheels or rollers 3, 3, will cause the figure 1 to have a rocking motion when it is propelled, either by gravity upon a cord, or by an impulse from the handle upon a surface.

Having described my invention, what I claim is:

1. In a toy, the combination of a body member; grooved rollers eccentrically mounted on said member; a rod pivotally attached to said member above the roller mountings; a second rod pivotally attached to said first mentioned rod and adapted to serve alternatively as a handle and a counterpoise.

2. In a toy, the combination of a body member; eccentrically mounted rollers thereon, each of said rollers having rims for surface travel and a groove to receive a cord therein, the said grooves of all the rollers being aligned; and a handle pivotally mounted on said member and comprising a jointed rod of two sections, the sections being so related that the handle may be extended when in use and folded when serving as a counterpoise.

In testimony whereof I affix my signature.

CHARLES GARNISS.
